Primary Examiner — Karen S Acker*Assistant Examiner* — Andrea Marie McKay(74) *Attorney, Agent, or Firm* — Georgi Korobanov(57) **CLAIM**

The ornamental design for an electromagnetic induction heater, as shown and described.

DESCRIPTION

FIG. 1 is a perspective view of an electromagnetic induction heater, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the electromagnetic induction heater that form no part of the claim.
